UNITED STATES PATENT OFFICE.

GEORGE W. DAGUE, OF OKLAHOMA, OKLAHOMA.

NONREFILLABLE BOTTLE.

Application filed May 1, 1922. Serial No. 557,532.

To all whom it may concern:

Be it known that I, GEORGE W. DAGUE, a citizen of the United States, residing at Oklahoma city, in the county of Oklahoma and State of Oklahoma, have invented certain new and useful Improvements in Non-refillable Bottles; and I do hereby declare the following to be a full, clear, and exact description of the invention, such as will enable others skilled in the art to which it appertains to make and use the same.

The present invention relates to non-refillable bottles, and aims to provide a bottle having a valve within the neck thereof, to prevent the bottle from being refilled, and novel means for retaining the valve in place.

Another object of the invention is the provision of a valve retaining tube fitted in the bottle neck, and novel means for securing such tube within the neck, so that the tube cannot be removed.

A further object is to provide a valved bottle neck construction comprising a novel assemblage of the component elements, providing a simple, practical and efficient device.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a vertical median section with the valve retaining tube in position ready to be locked.

Fig. 2 is a similar view showing the tube moved home and locked.

Fig. 3 is an enlarged sectional detail on the line 3—3 of Fig. 2.

Fig. 4 is an enlarged sectional detail on the line 4—4 of Fig. 1.

The bottle neck 7 has the passage 8 which is reduced at its lower end to provide a seat 9 for a ball valve 10, to prevent liquid being poured into the bottle for refilling same.

The valve 10 is retained in the bottle neck adjacent to the seat 9 by a retaining tube 11, which may also be made of glass or other material, the same as the bottle proper. The tube 11 is slid snugly into the passage 8, and its lower end is corrugated,

as at 12, or otherwise formed, so that when the bottle is tilted or inverted for pouring the contents therefrom, the ball in seating against the inner end of the tube 11 will permit the liquid to flow between the valve and tube. The valve is thus confined between the seat 9 and inner end of the tube 11, thereby preventing the ball from being removed.

The outer end of the tube 11 has an annular outstanding flange or head 13 to be disposed at the end or mouth of the bottle neck, and a gasket 14 of cork, rubber or other suitable compressible material surrounds the tube 11 between the end of the bottle neck and flange 13 to prevent leakage when the tube 11 is forced into place, as seen in Fig. 2.

Means is provided for locking the tube 11 within the bottle neck. Thus, the end of the neck has a notch 15 at the inside, and a bore 16 extending downwardly from said notch, with the lower end of the bore inclined to provide a bottom deflecting surface 17 and an opening 18 leading to the passage 8. The tube 11 is provided at the corresponding side with a recess 19 to register with the opening 18 when the tube 11 is forced home, and a lock ball 20 is arranged to enter the recess 19. A detent ball 21 is disposed within the passage or bore 16 above the lock ball 20, and the bore 16 is formed with a shoulder 22 at the upper end of the deflecting surface 17 into which the detent ball 21 can be forced, for retaining the ball 20 in place, as seen in Fig. 2. A lug 23 is integral with the flange 13 and tube 11 to enter the notch 15, and has a depending finger 24 to enter the bore 16 when the tube 11 is slid into place within the bottle neck.

In assembling the parts, after the bottle has been filled, the valve 10 is first dropped into the bottle neck, and the tube 11 is then slid part way into the bottle neck, with the finger 24 above the end of the neck, so that the balls 20 and 21 can be dropped down into the bore 16. The tube 11 is then pushed down into the bottle neck, so that the finger 24 enters the bore 16, as seen in Fig. 1, to contact with the ball 21. Then, as the tube 11 is forced home, the recess 19 moves into registration with the opening 18, for receiving the ball 20, and finger 24 in pushing down on the ball 21, forces the ball 20 through the opening 18 into the recess 19, the deflecting

surface 17 causing the ball 21 to be forced inwardly by the pressure on the ball 21. The ball 21 is then forced between the ball 20 and shoulder 22, and will retain itself in place frictionally, so that the balls cannot be loosened, and the ball 20 being partially within the opening 18 and partially within the recess 19, will securely lock the tube 11 in place, with the gasket 14 compressed to prevent leakage between the bottle neck and tube. Therefore, although the contents of the bottle can be decanted, liquid cannot be poured into the bottle while the valve 10 is seated with the bottle in upright position. It will be noted that the upward pressure on the tube 11, due to the tendency for the gasket 14 to expand, will tend to move the lock ball 20 upwardly or toward the end of the bottle neck, but in bearing against the detent ball 21, the balls cannot move reversely, owing to the ball 21 seating against the shoulder 22. The tube 11 cannot therefore be unlocked, so that it is impossible to remove the tube 11 and valve 10 without breaking the bottle neck.

Having thus described the invention, what is claimed as new is:—

1. A bottle neck having a valve seat therein, a valve seatable on said seat, a valve-retaining tube insertable into the neck, the neck having a bore, said tube having a recess to register with said bore, locking means within said bore to enter said recess and arranged to assume a locking position between said tube and neck, and a portion carried by the tube to enter said bore and force the locking means into said recess and locking position.

2. A bottle neck having a valve seat therein, a valve seatable on said seat, a valve-returning tube insertable in the neck, the neck having a bore, the tube having a recess to register with said bore, the neck having a shoulder, locking means within the bore to enter said recess and arranged to engage said shoulder after entering the recess for locking said means in place between the tube

and neck, and a portion carried by the tube to enter said bore and operable for forcing the locking means into the recess and locking position. 50

3. A bottle neck, a valve to be disposed in the bottle neck, a valve-retaining tube insertable into the neck, locking means in the neck adapted to be forced into a locking position between said tube and neck, and a portion carried by the tube to move against said locking means and force the locking means into locking position when the tube is forced into place in the neck. 55

4. A bottle neck having a valve seat therein, a valve seatable on said seat, a valve-retaining tube insertable in the neck, the neck having a bore, the tube having a recess to register with said bore, a portion carried by said tube to enter said bore, and balls in said bore, one ball being arranged to enter said recess for locking the tube in the neck, and the other ball being forced by said portion between the first named ball and neck for 65 retaining the balls in place. 70

5. A bottle neck having a valve seat therein, a valve seatable on said seat, a valve-retaining tube insertable in said neck, the neck having a downwardly extending bore 75 inclined at its lower end to provide a lower deflecting surface and an opening, said tube having a recess to register with said opening, the neck having a shoulder at the upper end of said surface, a finger carried by said tube 80 to enter said bore, a lock ball to be deflected by said surface through the opening and into said recess for locking the tube in the neck, and a detent ball between the lock ball and finger to be forced by the finger between 85 the lock ball and shoulder.

In testimony whereof I have signed my name to this specification in the presence of two subscribing witnesses.

GEORGE W. DAGUE.
